UNITED STATES PATENT OFFICE.

ISAAC B. MACOMBER, OF PORTSMOUTH, RHODE ISLAND.

TROUSERS-STRETCHER.

973,444.

Specification of Letters Patent. Patented Oct. 18, 1910.

Application filed December 23, 1909. Serial No. 534,708.

To all whom it may concern:

Be it known that I, ISAAC B. MACOMBER, a citizen of the United States, residing at Portsmouth, in the county of Newport and 5 State of Rhode Island, have invented a new and useful Improvement in Trouser-Stretchers, of which the following is a specification.

This invention relates to improvements in 10 trousers stretchers and pertains more particularly to an improvement in that type of stretchers adapted to be inserted into the legs of the trousers.

The object of the present invention is to 15 provide a construction wherein the parts may be folded, collapsed, or knocked down, in order to occupy comparatively small space for purpose of transportation, storage or the like.

20 The further object of the invention is to enable the parts to be folded with ease, facility and rapidity, and to be likewise as easily and quickly restored to operative or extended position.

25 Further and other objects will be later herein manifested and set forth.

Referring to the accompanying drawings in which like characters of reference designate similar parts throughout the several 30 views, Figure 1 is a front elevation of the trousers stretcher showing the same in expanded position, Fig. 2 is an end elevation partly in section taken on the line 2-2 of Fig. 1, Fig. 3 is a view similar to Fig. 1, 35 showing the parts in contracted position ready for insertion into the legs of the trousers, Fig. 4 is a detail view partly in section of the connection between the side members of the stretcher which allows the side members to be folded, and Fig. 5 is a detail view being a section taken on the line 40 5-5 of Fig. 1.

In the drawings, *a*, *a* designate generally 45 the two side members of which each stretcher is composed. Each side member consists of a pair of bow-shaped bars 1 and 2 which have their inner ends extended at substantially right angles as indicated at 3, and adapted to have their adjoining faces in 50 abutting relation, as shown in Fig. 4. Each end of the supporting bars 1 and 2 is bifurcated to receive thin flexible metal creasing bars 4 and 5 respectively, the bars 4 and 5 being held in the bifurcated ends by pins 55 6 or the like. It will be observed with respect to Fig. 1 that the creasing bars 4 and 5

are in substantial alinement with each other. A sheet metal casing or housing 7 is provided which incloses the abutting right angular ends of the bars 1 and 2, this housing being formed of a piece of sheet metal which is wrapped around the ends 3, 3 and has its overlapping end parts secured as by a rivet 8, shown in Fig. 5. A spring of the flat type 9 has one end secured to the 60 supporting bar 1 as at 10, and has its opposite end curved so as to engage between one side wall of the housing 7 and the adjacent face of one of the right angular ends 3, as shown in Fig. 4, it being understood that 65 sufficient space is left between the said side wall of the housing and the adjoining right angular end 3, to accommodate the spring in a manner depicted in Figs. 4 and 5. It will thus be observed that each of the side 70 members is composed of two parts which can be collapsed and folded with respect to each other, which is easily done by moving one of the parts against the tension of the spring so as to lie in engagement with the 75 other part of that member.

The means for expanding the two side members *a* consist of a pair of arms 11, each having a long leg 12 and a short leg 13, the latter being arranged at an obtuse angle to 80 the former and having their free extremities curved inwardly, as shown at 14. The free ends of the legs 12 are pivoted to central points along the length of the side members *a*, this being accomplished by the provision 85 of U-shaped clips 15 suitably supported on the bars 1, and pins 15' which extend through the free ends of legs 12 and the two sides of the clips 15, the free ends of legs 12 being received in the space between 90 the two sides of the clips 15. The two arms 11 are pivoted together by means of two substantially U-shaped members 16 which embrace the arms 11 at the inner ends of legs 12 and 13 thereof, a pin 17 being passed 95 through the inner ends of the members 16. The means for operating the arms 11 from collapsed position to extended position and vice versa, consist of a guide member 18 which is freely slidable along the length of 100 the legs 13 of arms 11. The guide member 18 is preferably constructed of a piece of metal which completely incloses the legs 13 and which is conveniently operated by a bail member 19, which latter consists of a hand 105 engaging loop 20, the free ends of which are turned at right angles as shown in Fig.

2 and passed through points intermediate | porting bar, and means for expanding and
the length of the guide member 18, the ex- contracting said side members.
tremities of the ends of loop 19 being
headed as shown at 21. By reference to
5 Fig. 1 it will be observed that when the
parts are in extended position the right
angular ends of loop 19 will engage with the
inner side faces of the inwardly curved ex-
10 tremities 14 of the legs 13 of arms 11 and
will thereby restrict the movement of the
guide member with respect to the legs 13
preventing disengagement of the parts in
15 an obvious manner. The bars 1 are also
provided with the clips 22 by means of
which the bottom of the trousers legs are
secured to the side member *a*.

In the operation of stretching and creasing trousers two stretchers are used one for
each leg, each stretcher being contracted
20 into the position shown in Fig. 3 by moving
the guide member 18 inwardly, after which
the stretchers are inserted into the legs of
the trousers. The clips 22 are then turned
25 down on the material of the trousers legs to
clamp them to the side member *a*. The
stretcher is then expanded by moving the
guide member 18 outwardly, causing the
30 creasing bars 2 to be placed under the re-
quired tension effecting proper creasing of
the trousers leg.

It will be seen from the above that the
entire structure can be made of metal and
being constructed in accordance with the in-
vention will be found to be light in weight,
35 serviceable, and efficient in operation and
can be easily applied or removed and readily
collapsed and restored to extended or oper-
ative position as is desired.

Having thus described my invention, I
40 claim as new and desire to secure by Letters
Patent;—

1. A trousers stretcher comprising two
side members each consisting of two sup-
porting bars having their adjacent ends
45 turned at right angles and in engagement
with each other, a housing loosely embracing
said right angular ends, a spring in the
housing for holding said right angular ends
50 in close engagement with each other and
with one wall of the housing, said bars be-
ing foldable against the tension of the
spring, a creasing bar carried by each sup-

porting bar, and means for expanding and
contracting said side members.

2. A trousers stretcher comprising two 55
side members, each side member being com-
posed of two parts, said parts having their
inner ends arranged adjacent each other, a
housing loosely engaging said ends of the
parts, means in the housing for holding said 60
ends of the parts in engagement with each
other and with one wall of the housing, and
means for expanding and contracting said
side members.

3. A trousers stretcher comprising two 65
side members, each consisting of two sup-
porting bars having their adjacent ends
turned at right angles and in engagement
with each other, a housing loosely embracing
70 said right angular ends, a flat spring secured
to one of said bars and having its opposite
ends curved and disposed in said housing to
engage one of said right angle ends to hold
75 said right angular ends in engagement with
each other and with one wall of the housing,
said bars being foldable against the tension
of the spring, a creasing bar carried by each
supporting bar, and means for expanding
and contracting said side members.

4. A trousers stretcher comprising two 80
side members, each side member being com-
posed of two parts, each of the parts includ-
ing a bow-shaped bar, and a creasing bar se-
cured between the ends of each bow-shaped
85 bar, the bow-shaped bars of each part having
their inner ends arranged in juxtaposition
to each other, and means to embrace said
inner ends of said parts.

5. A trousers stretcher comprising two 90
side members, each composed of two bars
having their adjacent ends turned at right
angles and in engagement with each other,
means loosely embracing said right angular
95 ends, a spring for holding said right angular
ends in intimate contact with each other and
with one wall of said means, and means for
connecting the side members.

In testimony whereof I have signed my
name to this specification in the presence of
two subscribing witnesses.

ISAAC B. MACOMBER.
